SPRING SUPPORT FOR UPHOLSTERY
AND THE LIKE

Ermin Stuart Copeland, David Bertram Porter,
and Walter Van Wyck, Wingham, Ontario,
Canada, assignors to Fry & Blackhall, Limited,
Wingham, Ontario, Canada, a company of
Ontario

Application May 13, 1943, Serial No. 486,758
In Canada February 24, 1943

3 Claims. (Cl. 5-247)

Our invention relates to improvements in spring supports for upholstery and the like.

Due to the fact that steel has recently been placed on civilian restricted and prohibited lists, it is necessary to devise other types of spring support for upholstery and the like. As a result, many proposals have been made in this field and as a matter of fact, many years ago a variety of wooden springs were invented and proposed for use but without practical success. Many of these proposals are cumbersome or have had severe limitations. Almost all have had as features the bow of "the bow and arrow" or the spring principle of the "springboard of the old swimming hole." To harness these qualities of springing into a simple, practical and noiseless unit and to use the spring qualities mentioned in multiples in the said unit, to ease the strain at any one point, to equalize the flexing of the spring unit over all the parts intended to flex and to provide against damage to the flexing members by sudden shock, is the goal sought and achieved by this invention.

It is, therefore, an object of the invention to avoid the disadvantages of the prior art and to devise a construction of spring support which will dispense with the use of metal to a maximum extent in its construction to conform to government restrictions and allow of its replacement by wood and yet at the same time achieve a flexibility and durability equal to that hitherto attained in an all metal construction.

In the drawings:

Fig. 1 is a perspective view of our wood spring construction.

Fig. 2 is a cross sectional view through Fig. 1.

Fig. 3 is a sectional view taken from front to rear of the construction illustrated in Fig. 1 and showing by dotted lines the position of the front portion of a spring when under load.

Fig. 4 is a similar view to Fig. 3 showing by dotted lines the position of the rear portion of a spring when under load.

Fig. 5 is a similar view to Figs. 3 and 4 showing in dotted lines the position a spring assumes when the centre or main portion of the spring is under load.

Figs. 6 and 7 are sectional views of alternative constructions.

In the drawings like characters of reference indicate corresponding parts in each figure.

A is a spring unit. Three of these units are usually employed in a chesterfield or davenport seat and three units to form the back. In a chair of similar construction, one spring unit is em-

ployed in the seat and one in the back. Each spring unit A is provided with a main supporting frame 1 similar to that usually employed and comprising the front and rear bars 2 and 3 and side bars 4 and 5.

Between the side bars 2 and 3 are turnably mounted rocking members 6 and 7 on which the upholstery springs 8 are directly mounted. The springs 8 are preferably four in number in each

10 unit A.

The members 6 and 7 are in the form preferably of rectangular bars provided at their ends with trunnions 9 and 10 freely fitting holes 11 and 12 formed in the side bars 4 and 5. The trunnions 15 9 and 10 and holes 11 and 12 are provided with a suitable lubricant to prevent friction.

The springs 8 are formed of hard wood such as rock elm, hickory or ash and treated to prevent the penetration of moisture and are in the form 20 of a bow (that is, a bow in a bow and arrow) and are arranged parallel to each other in each unit A. The ends 13 and 14 of the bow are anchored respectively to the rocking members 6 and 7 so that when the springs 8 are centrally under load, they tend to turn the members in opposite directions as indicated by arrow in Fig. 5.

When the front portion only of the spring 8 is under load, the member 7 only turns; the rear portion being held from movement by the bar 15

30 which prevents the upward movement of their rear portion. When the rear portion of the spring 8 is the only portion under load, the member 6 only turns; the front portion of the spring being held from movement either by the bar 16 as

35 in Fig. 6 or by the anchor device 17 of Figs. 1, 3, 4 and 5 and which consists of the riders 18 secured to the main portion of each spring 8 as indicated at 19, the connecting strip 20 and the fabric strips 21 secured to the strip 20 at one end and to the front bar 2 of the main supporting frame. The riders 18 and the strip 20 are also

40 formed of wood.

In order to take up shock when the springs 8 come under heavy load, we provide the small tension springs 22 secured to the members 6 and 7 to resist their turning movement and gradually take up the applied load preventing any liability of the springs 8 cracking.

What applicants claim to be novel is the use in 50 each spring unit A of two rocking members 6 and 7, the ends of which fit rockably in the frame. These rocking members form the anchor points for the two ends of loop flexing or spring members 8 of sufficient size, weight and number to fill

the desired size of seat or back and to give the desired resiliency.

The reason for the use of rocking members as anchor supports for the ends of the spring members 8 is to provide a flexible knee action to the spring impossible if the flexing member ends are rigidly and immovably anchored. The movement of the rocking member provides against sudden shock between the end bows of the spring 8 and to the springboard portion 8x by permitting the members 6 and 7 to turn slightly when the spring is under pressure, thus constantly changing, during the period of being compressed, the point at which the greatest strain comes. This knee action brings the whole flexing member into play and greatly lessens any possibility of breakage through shock at any point.

It is, however, necessary to control the action of the rocking members 6 and 7 to give the desired effect. Without control these members would turn too far in either forward or backward action and would bring about complete negation of the results desired. This control is provided by the cross members 15 and 16 which are used across the frame of each spring unit parallel to but preferably two inches outward from each rocking member 6 and 7 and above the lower part of the flexible bow spring member 8. This prevents the back of the spring unit from tipping upward and letting the front go too far down and likewise it prevents the front from tipping too far up and letting the back too far down.

Further if the springs 8 are compressed most forcibly at the back it brings the flexibility of each spring completely into play from the front cross member 16 or 20 to the rocking member 6 at the opposite side. If the spring unit is compressed most forcibly at the front, it brings the flexibility of each spring member completely into play from the back cross member 15 to the rocking member 7 at the opposite side.

A further shock absorber and equalizer is provided by the use of a suitable number of helical springs of satisfactory gauge and length to control the extent to which the seat may be compressed either at the front or back, separately or equally together. Not only does the use of these helical springs prevent the spring unit from compressing to the point of hitting bottom, but the torsion effect of the spring ensures more resiliency comeback after compression is released and acts as a buffer against sudden shock or strain. These helical springs flexibly connect the rocking members at right angles to said members.

When a spring edge is required, the riders 18 which are preferably of the same flexible material as is used in the spring member 8 are securely fastened to the top of member 8 as far toward the part of that member which will permit the rider to extend beyond it but still parallel with its top surface. At the point at which a spring edge is required, a cross member 20 joins the riders at right angles. This cross member while flexible is of sufficient weight to hold tacks securely. Webbing or other satisfactory securing material is used to "tie down" the spring

edge. This tying is done with sufficient strength so that when a spring edge is used, the front controlling cross member 16 otherwise used parallel to the front rocking member 7 is no longer necessary and is eliminated.

Although we have described our device as used for supporting seat upholstery of a ches-terfield, davenport, or a chesterfield chair, it can equally be applied to the upholstered backs of these articles of furniture and also not only to upholstered furniture but to bed spring supports for mattresses and further to verandah furniture in which the upholstery is dispensed with and the spring 8 suitably colored to give a decorative effect.

In Fig. 7 we have shown a further modification in which the centre portion of each spring 8 is cut away and the spring ends connected by strips 23 and 24 securing canvas or other flexible material across the interspace to provide a soft flexible seat.

What we claim as our invention is:

1. The combination with a main support and a plurality of parallel bow springs set with their bow backs uppermost and the extremities of their opposing ends parallel, of a rocking member turnably mounted in the main support to which one end of each bow is secured, a rocking member also turnably mounted in the main support to which the other end of each bow is secured, means for resiliently resisting the turning movement of the rocking members in an outward direction when the bow springs are depressed, and means for preventing the upward movement of either end of the bow while permitting free downward movement.

2. The combination with a main support and a plurality of parallel bow springs set with their bow backs uppermost and the extremities of their opposing ends parallel, of a rocking member turnably mounted in the main support and to which one end of each bow is secured, a rocking member also turnably mounted in the main support and to which the other end of each bow is secured, tension springs connecting the rocking members together at a point above their axial centers to resist their turning movement in opposite directions, and means for preventing the upward movement of either end of the bow while permitting free downward movement.

3. The combination with a main support and a plurality of parallel bow springs set with their bow backs uppermost and the extremities of their opposing ends parallel, of a rocking member turnably mounted in the main support to which one end of each bow is secured, a rocking member also turnably mounted in the main support to which the other end of each bow is secured, means for resiliently resisting the turning movement of the rocking members in an outward direction when the bow springs are depressed, and means for preventing the inward turning movement of either rocking member while permitting free outward movement.
